UNITED STATES PATENT OFFICE.

JULES ADRIEN BOUILLON, OF BAZOCHE EN HOULMES, FRANCE.

ACETYLENE-GENERATOR.

1,084,691.

Specification of Letters Patent.

Patented Jan. 20, 1914.

Application filed March 5, 1913. Serial No. 752,034.

To all whom it may concern:

Be it known that I, JULES ADRIEN BOUILLON, citizen of the Republic of France, residing at Bazoches en Houlmes, Orne, France, have invented new and useful Improvements in Acetylene-Generators, of which the following is a specification.

This invention relates to acetylene generators and more particularly to acetylene generators intended for use on motor cars for supplying the headlights thereof.

In the annexed drawings: Figure 1 is a side elevation of an apparatus constructed in accordance with the invention, partially broken away, Fig. 2 is a plan view, partly in section along A—A Fig. 1, the lids being removed. Fig. 3 is a vertical section taken approximately along B—B, Fig. 2, Fig. 4 is a vertical section along C—C, Fig. 2, one of the carbid receptacles being shown partly in elevation, Fig. 5 is a plan view of the generator proper, the outer and one of the inner lids being removed.

The apparatus comprises an outer rectangular casing divided into two compartments or chambers 1 and 2 by a partition 3. The chambers 1 and 2 are covered at the top by lids 4 and 5, respectively. The chamber 1 contains the generator proper which is formed of a casing 6 divided into two parts by a vertical partition 7 and provided with a cup shaped lid 8 having handles 10, which permit of easily removing the generator casing 6 from the chamber 1 of the outer casing. The casing 6 is also provided, on its under face with projections or feet 11.

In each of the compartments of the casing 6 is placed a carbid receptacle 12 having a rectangular shape and closed at the top by a lid 13 provided with a ring 9 for the easy removal thereof. Under the lids 13, the receptacles 12 are provided with cross bars 17 which may be used as handles for removing the receptacles from the casing 6. The receptacles 12 have also projections or feet 15 at the bottom and the side walls thereof are provided with holes 16 through which water having entered the compartments of the casing 6 can reach the carbid contained in the receptacles 12. The water feed is regulated in the following way: In the middle of the generator casing 6 the partition 7 forms a vertical cylinder 18 (Figs. 4 and 5) through which extends a sleeve 19 secured to, or integral with, the bottom of the casing 6. The interior of said sleeve 19 is

in communication with the water contained in the chamber 1 outside the casing 6 through a hole 23 in the bottom of the said casing. The hole 23 may be closed from the top by means of a needle valve 20 having a pointed end 22 which extends through the hole 23 and carrying at its upper end a hand wheel 21. The valve 20 is threaded at its upper part and screwed through a nut 24 which is permanently screwed into the upper end of the sleeve 19, which latter is externally threaded and receives a nut 25 by means of which the lid 8 is held with a tight joint upon the casing 6. A metal washer 26 and a resilient washer 27 are interposed between the nut 25 and the lid 8. The sleeve 19 has in its lower part openings 28 and the cylinder 18 has also openings 29 at various levels.

From an opening in the lid 8, extends a gas pipe 30 which is connected through a flexible pipe 30^a to a small regulating valve 31 mounted on a condensating chamber 32 to which the acetylene gas formed is led and in which it leaves the moisture carried therewith. The condensating chamber 32 is formed of a cylindrical casing secured on a side wall of the outer casing 2 by means of a strap 33 and closed at the top by means of an internally threaded cap 34. At its lower end, it is provided with a drain opening closed by means of a flexible washer and a threaded cap 35.

The upper part of the condensating chamber 32 is connected by a metal pipe 36 (Fig. 3) and a flexible pipe 37 to a metallic pipe 38 secured to the purifier, the pipe 38 branching into two parts 39 which extend into the lower parts of the two cylinders 40 forming the purifier. Both cylinders 40 are located in the chamber 2 of the outer casing and closed at the top by an internally threaded cap 41, a flexible washer 42 being interposed to make a tight joint. In the cylinders 40, above the branches 39, is located a filtering screen by means of which the gas is physically purified and upon which substances performing a chemical purification are located. The filtering screen is formed of a perforated plate 43 which carries a plate 44 having finer perforations, and a felt disk 45. Upon the filtering screen I place any suitable chemical substances, well known in the art, which are adapted to chemically purify and cleanse the formed gas. The cylinders 40 of the purifier are carried on

springs 46 to avoid the purifying substances being rammed or clogged against the filtering screen by the shocks or jerks imparted to the motor car body carrying the acetylene generator. The cylinders 40 are connected together at their upper part by a pipe 47 from which extends a pipe 48 connected to a flexible pipe 49 which extends through the wall of the casing 2 as shown in Fig. 10 2 and is in communication with the headlights of the motor car.

In operation, water is poured into the chamber 1; when the valve 20 is raised, the water enters the sleeve 19 and flows through 15 the openings 28 into the annular space between the sleeve 19 and the cylindrical wall 18. The water rises in said annular space up to the lower opening 29, flows into the corresponding compartment of the casing 6, 20 and rises in the corresponding receptacle 18 through the openings 16 in the same. As the opening 29 leading the water to the other carbid receptacle is on a higher level than that just referred to, the water will react on 25 the carbid in the latter receptacle only when the carbid in the first receptacle has been exhausted. As the water in the compartment of the casing 6 comes into contact with the carbid through the holes 18 slowly and 30 progressively, the rising of the water being checked by the pressure of the gas, the gas is generated in a quantity corresponding to the consumption thereof and the sudden production of a considerable amount of gas, 35 which would be dangerous, is entirely avoided. The gas escaping from the generator proper is led through the pipes 80, 80^a to the condensator 82 cooled by the outer air, whereby the gas is freed from its moisture. 40 The gas passes then through the purifying chambers 40 where it is submitted to a physical and a chemical purification. The gas so treated is quite well adapted for immediate use.

45 Various details may obviously be modified in the construction shown without departing from the scope of my claims.

Having now described my invention, what I claim as new and desire to secure by Letters Patent is:

1. An acetylene gas generator, embodying therein an outer casing divided into a plurality of compartments of which one forms a liquid chamber, a carbid container embodying an orificed casing directly within the said liquid chamber and containing a plurality of carbid receiving chambers, means for controlling the orifice in said last named casing whereby varying quantities of liquid are admitted from said liquid chamber to said carbid container, a partition within said orificed casing having means in different horizontal planes whereby liquid is admitted to the carbid receiving chambers 60 from the orificed casing at different times,

and means for conducting the gas out of the generator.

2. An acetylene gas generator, embodying therein an outer casing divided into a plurality of compartments of which one forms a liquid chamber, a carbid container embodying an orificed casing directly within the said liquid chamber and containing a plurality of carbid receiving chambers, means for controlling the orifice in said last named casing whereby varying quantities of liquid are admitted from said liquid chamber to said carbid container, means in a compartment adjacent said liquid chamber for purifying the gas, a partition within said orificed casing having means in different horizontal planes whereby liquid is admitted to the carbid receiving chambers from the orificed casing at different times, and means for conducting the gas out of the generator.

3. An acetylene gas generator, embodying therein an outer casing divided into a plurality of compartments of which one forms a liquid chamber, an orificed casing directly within said liquid chamber, a plurality of perforated carbid receptacles within said last named casing, means for controlling the orifice in said orificed casing, a partition between said receptacle having openings there in in different horizontal planes whereby liquid is admitted from said orificed casing into said perforated carbid receptacles at different times, and means for conducting the gas out of the generator.

4. An acetylene gas generator, embodying therein an outer casing divided into a plurality of compartments of which one forms a liquid chamber, an orificed casing directly within said liquid chamber, a plurality of perforated carbid receptacles within said last named casing, means for controlling the orifice in said orificed casing whereby liquid is admitted from said liquid chamber into said orificed casing, a partition between said receptacles having means therein at different horizontal planes for admitting liquid at different times to said receptacles, means in a compartment adjacent the liquid chamber for purifying the gas generated in said carbid receptacles, and means for conducting the purified gas out of the generator.

5. In an acetylene generator, in combination, an outer casing divided into two chambers, an inner casing in one of the chambers, divided into two compartments, a carbid receptacle in each compartment, the walls of said receptacles having holes arranged one above the other, a central sleeve in said chamber, means for regulating the flow of water from the said chamber into the central sleeve, the sleeve having holes in its lower part, a cylinder around said sleeve, said cylinder having an opening running into one

of the compartments and another opening on a higher level than the former, running into the other compartment, a moisture condenser formed of a hollow cylinder in communication with the inner casing, purifiers in the other chamber of the outer casing, communicating at one end with the moisture condensator, and at the other end with the utilizing apparatus, said purifiers containing screens for straining the gas and substances capable of chemically removing the

impurities of the gas, and means for resiliently supporting the purifiers in the outer casing, substantially as described and for the purpose set forth.

15

In testimony whereof I have signed my name to this specification in the presence of two subscribing witnesses.
